UNITED STATES PATENT OFFICE.

ABRAHAM SONDACK, OF NEW YORK, N. Y.

AWNNG-OPERATING MECHANISM.

Application filed November 8, 1924. Serial No. 748,714.

To all whom it may concern:

Be it known that I, ABRAHAM SONDACK, a citizen of Russia, residing at Bronx, New York city, county of Bronx, and State of New York, have invented certain new and useful Improvements in Awning-Operating Mechanisms, of which the following is a specification.

This invention relates to improvements in awning operating mechanisms, and has particular reference to a locking device therefor.

An object of the invention is to provide an improved mechanism wherein the operating parts thereof are released from a normally locked condition by the insertion of an operating handle in the casing of the mechanism.

Another object is to provide a locking device for the operating mechanism which is actuated to a non-locking position by engagement therewith of an operating handle and which is restored to its locking position by the withdrawal of said handle.

The above and other objects will appear more clearly from the following detailed description, when taken in connection with the accompanying drawings, which illustrate preferred embodiments of the inventive idea.

In the drawings—

Figure 1 is a vertical longitudinal section showing one form of the invention with the mechanism in its operative position;

Figure 2 is a similar view showing the mechanism in its inoperative position;

Figure 3 is a section on the line 3—3 of Figure 1;

Figure 4 is a section on the line 4—4 of Figure 2;

Figure 5 is a view similar to Figure 2 showing a slightly different form of the invention;

Figure 6 is a section on the line 6—6 of Figure 5; and

Figure 7 is a fragmentary elevation, partly in section, of a slightly different form of operating handle.

Referring more particularly to the form of the invention shown in Figures 1 to 4, the numeral 7 indicates a casing of substantially rectangular formation open at one end and provided upon said end with a base

plate 8 designed to be attached to a wall or other support. The open end of the casing is closed by means of a closure plate 9 countersunk in the inner face of the base 55 plate 8 and detachably secured thereto by means of screws 10 or other suitable fasteners.

In the top of the casing 7 the same has mounted therein a bushing 11 in which the squared lower end of an operating shaft 12 is supported. This shaft is of the usual construction and is connected at its upper end through gears (not shown) or other well known mechanism utilized to raise and lower the awning when the shaft 12 is rotated. The bushing 11, which is rotatably mounted in the casing, is provided with an extension 13 projecting into the casing and having secured thereto the bevel gear 14. 70 The extension 13 has a bearing in a supporting plate or partition 15, preferably cast integrally with the sides of the casing, and said partition also forms a support for the bevel gear 14. 75

The front 16 of the casing is provided with an opening 17, in which the hub 18 of a bevel gear 19 is rotatably mounted. The inner end of the hub 18 is reduced and engaged in a supporting flange 20 depending 80 from the supporting plate or partition 15, said flange having an opening 21 therein for a purpose which will presently appear.

The invention further provides means for locking the gears 14 and 19 against rotation when the mechanism is not in use, which means is normally in an operative position and capable of being moved to an inoperative position by the insertion of a portion of the operating handle 22 into the 90 casing. This means is preferably in the form of a locking member, generally indicated by the numeral 23, supported within the casing 7, preferably adjacent the rear or closure plate 9. The locking member includes a locking extension 24 projecting through an opening 25 in the partition 15 and engageable between adjacent teeth of the gear 14 to prevent rotation of said gear when the locking member is in its operative 100 position. The lower extremity of the locking member 23 is provided with a lateral

projection 26 extending forwardly and formed upon its end with an enlarged portion 27 having an inclined surface at its forward end for a purpose which will presently appear. Depending from the projection 26 is a rod 28, the lower end of which extends through the bottom of the casing 7. A coil spring 29 is interposed between the projection 26 and the bottom of the casing to yieldably exert an upward pressure on the locking member to retain it in its locking position. The handle 22 is formed with a lateral projection 30 of rectangular formation and capable of fitting into the hub 18 of the gear 19 and extending from said projection 30 is a pin 31 having a tapered head 32. When the projection 30 and pin 31 are inserted into the hub 18 the pin 31 extends through the opening 21 in the flange 20 and the head 32 engages the enlargement 27 of the locking member 23. As the pin 31 is forced inwardly, it will be obvious that the head 32 will force the locking member 23 downwardly against the tension of the spring 29 and thus disengage the locking extension 24 from the gear 14. The handle 22 may now be turned to impart a rotary movement to the shaft 12 to either raise or lower an awning.

Upon withdrawal of the handle the head 32 of the pin 31 will be disengaged from the enlargement 27 of the projection 26 and the coil spring 29 will thereupon force the locking member upwardly until the extension 24 thereof is again engaged with the gear 14.

In the form of the invention shown in Figures 5 and 6, the construction of the parts is identical with that previously described with the exception of the partition 15 and the locking member 23. In this instance, the partition 15, instead of having only one opening 25 therein, is provided with two openings 33 through which two locking extensions 34 project. These locking extensions are formed upon the ends of a transversely extending plate 35 forming a part of the locking member 23. By the provision of the two locking extensions 34, it will be apparent that said extensions when in engagement with the gear 14 will effectively prevent rotation thereof in either direction. The operation of the mechanism is precisely the same as described in connection with the embodiment shown in Figure 1.

In Figure 7, the handle 36 is provided with a lateral projection 37 similar to the projection 30 but made with an opening 38 therethrough in which the slideable pin 39 is mounted. This pin is provided at one end with a head 40 and at its other end with a knob 41, which latter facilitates the sliding of the pin in the projection 37. With this construction the locking member 23 may be operated simply by sliding the pin

39 back and forth without withdrawing the handle from its operative position.

What is claimed is:

1. In an awning operating mechanism, the combination of a casing, coacting operating elements in said casing, a partition in said casing having a depending flange provided with an opening therein, a hub for one of said operating elements having a bearing in said casing and also in said depending flange, a locking member slidably mounted in said casing and having a locking extension projecting through said partition into engagement with one of said operating elements, a handle capable of connection to said operating elements by the insertion of a portion thereof into the casing, said handle also having a pin engageable with a portion of said locking member when the handle is connected to said operating elements to withdraw said locking extension from engagement with the operating element, and a spring interposed between the casing and said locking member for yieldably maintaining the same in its locking position and for restoring the same to such position after the handle is disconnected from said operating elements.

2. In an awning operating mechanism, the combination of a casing, coacting operating elements one of which has a bearing in one side of said casing, a locking member slidably supported in said casing and normally engaged with the other of said elements, means insertable into said casing for operating said elements and operable by its insertion to move said locking member to an inoperative position, and a spring interposed between said locking member and casing for yieldably maintaining said locking member in its operative position and for restoring the same to an operative position when the first named means is withdrawn from said casing.

3. In an awning operating mechanism, the combination of a casing, coacting operating elements one of which has a bearing in one side of said casing, a locking member slidably supporting adjacent the opposite side of said casing and normally engaged with the other of said elements, means insertable into said casing for operating said elements and operable by its insertion to engage and move said locking member to an inoperative position, and a spring interposed between said locking member and casing for yieldably maintaining said locking member in its operative position and for restoring the same to an operative position when the first named means is withdrawn from said casing.

4. In an owning operating mechanism, the combination of a casing, coacting operating elements in said casing, a partition in said casing in which said elements have a bear-

ing, a slidable locking member projecting through said partition and normally engageable with one of said elements to prevent rotation thereof, and a handle having a portion insertable into said casing and through said partition and connected to said elements for operating the same, and also

having means engageable with said locking member when said portion of the handle is inserted to actuate said locking member to **10** an inoperative position.

In testimony whereof I have affixed my signature.

ABRAHAM SONDACK.
